CLAIM

The ornamental design for a specimen collection container, as shown and described.

DESCRIPTION

FIG. 1 is a perspective view of a specimen collection container according to my new design;

FIG. 2 is a front side elevational view of the specimen collection container of FIG. 1;

FIG. 3 is a rear side elevational view of the specimen collection container of FIG. 1;

FIG. 4 is a left side elevational view of the specimen collection container of FIG. 1;

FIG. 5 is a right side elevational view of the specimen collection container of FIG. 1;

FIG. 6 is a top plan view of the specimen collection container of FIG. 1; and,

FIG. 7 is a bottom plan view of the specimen collection container of FIG. 1.

The broken lines depict portions of the specimen collection container that form no part of the claimed design.
